UNITED STATES PATENT OFFICE

2,631,548

LATCHING MEANS FOR GONDOLA CAR
DROP ENDSJames S. Swann, Homewood, Ill., assignor to
Standard Railway Equipment Manufacturing
Company, Chicago, Ill., a corporation of Delaware

Application July 16, 1949, Serial No. 105,255

9 Claims. (Cl. 105—406)

1

This invention relates to an improved latching means for the drop ends of gondola cars.

Some gondola cars are provided with ends which are pivoted at their lower outer corners to the corner structure of the car so that said ends may be lowered inside upon the floor of the car whereby extra long lading may be loaded upon two of such cars in end to end relation as is sometimes done. Extra long telephone poles, pipe and the like are sometimes shipped in this manner.

Through the rough usage these drop ends are subjected to they frequently become distorted to the extent that it is very difficult, if not impossible, with the conventional locking means to lock said ends in vertical position. It is, therefore, the principal object of my invention to provide a latching means for such ends having adjustable means associated therewith whereby even a distorted end may be locked in its vertical position.

It is a further object of the invention to mount the movable latching bar under the top chord of the drop end and to confine the whole movable part of the locking mechanism within the overall width of said top chord.

Other objects and advantages of the invention will appear in the following description thereof.

Referring now to the accompanying drawing, forming part of this application, and wherein like reference characters indicate like parts.

Fig. 1 is a top plan view of fragmental parts of a gondola car side wall and drop end showing the improved latching means applied thereto.

Fig. 2 is a cross section on line 2—2 of Fig. 1.

Fig. 3 is an end view of Fig. 1.

Fig. 4 is a view similar to Fig. 3 showing the addition of a locking cam to insure the latching bar and operating lever remaining in locked position.

Fig. 5 is a perspective view of the parts of the latching mechanism as they would appear in locked position.

In the drawings, 10 represents the end portion of the side plate of a railway gondola car, said side plate usually consisting of an ordinary bulb angle comprising flange 11, web 12 and bulb 13. The side sheathing is indicated at 14, the outer vertical margin of which is turned at substantially right angles thereto forming an inwardly facing flange 15. The end frame is formed of a Z-section comprising a flange 16 resting flatwise against side sheathing 14, a web portion 17 overlapping and resting flatwise against flange 15, and an outturned flange 18.

A plate 20 is secured to flange 11 of the side plate by a pair of rivets 21, said rivets extending

2

through plate 20, flange 11, side sheathing 14 and flange 16, holding all of said parts together in fixed relation. Between rivets 21 said plate 20 is provided with a series of rack teeth 22 which extend vertically and transversely across said plate 20. An adjustment bracket is shown at 23, having disposed across one face thereof a series of rack teeth 24 meshing with rack teeth 22 of plate 20. A hole 25 is provided through flange 16, side sheathing 14, flange 11 and plate 20, and a laterally elongated hole 26 is provided through the adjustment bracket. A bolt 27 extends through holes 25 and 26 which holds bracket 23 firmly against plate 20 with the cooperative rack teeth 24 engaged. The upper inner corner of the bracket 23 is chamfered or cut-away providing the inclined surface 28. Bracket 23 is, therefore, adjustable inwardly and outwardly in respect to the car by simply loosening bolt 27 until rack teeth 20 may be separated, the bracket moved to the desired location and the bolt again tightened.

The drop end is formed of a corrugated plate 30 having a top flange 31 inwardly turned, upon which is riveted the web 32 of the top chord, the bulb of which is shown at 33 and the flange at 34. At the bottom corners the end is hinged (not shown) in any acceptable manner as is common to the vertical portion of the adjacent end frame, so that the end may swing inwardly and downwardly against the floor of the car. When in upright position the vertical sides of the plate 30 are provided with side flanges 35. Slightly below the horizontal plane of the bottom of the bulb 33 of the end top chord, a pair of aligned holes 36—37 is formed respectively in the plate 30 and flange 34 of the end top chord inwardly of the sides of the car. These holes are to pivotally receive the end portions 38 of a pin extending through the cylindrical end 39 of the locking bar 40, which bar 40 extends outwardly beyond the end of the drop end top chord so as to occur in locking position between the outer end of bracket 23 and flange 15 of side sheathing. (See Fig. 1.) In this position a stop lug 41 extends upwardly from cylindrical portion 39 and contacts under surface of flange 31 and thereby limits the counter-clockwise movement of locking bar 40. The clockwise movement of said bar 40 is limited by contact with outer edge of flange 31, as clearly shown in the upper dotted line showing of bar 40 in Figs. 3 and 4. It will be noted that in this upper portion, the outer end of bar 40 is above adjustment bracket 23 and consequently the end may be dropped inwardly. Cylindrical portion 39 is in length substantially equal to the distance between end plate 30 and flange 34 (Fig. 2) and the por-

tion 38 which extends through the end plate 30 is provided with a squared end upon which is mounted a depending handle 42, occurring outside of the car end for convenient access by a trainman.

In operation, when it is desired to lower the end, a trainman would grasp handle 42 and rotate same clockwise until locking bar 40 was raised above adjustment bracket 23, at which time the end could be pushed inwardly and downwardly until resting on the car floor. The advantage of the adjustability of the adjustment bracket is that in case the car end or side should become bent to the extent the locking bar 40 could not be lowered behind the adjustment bracket 23, the bracket 23 may be moved in the direction required until said bar 40 would drop in place and bracket 23 then secured in that position and the car thereby kept in service. It will also be noted that the locking bar and handle are maintained within the bounding planes of the drop end bulb angle so that when the end is lowered poles or rails passing thereover will rest upon bulb 33 of the bulb angle and not contact handle 42.

In cases where it may be desired to positively prevent any jumping of the locking bar 40, due to rough track or the like, sufficiently for the drop end to accidentally lower, I have shown in Fig. 4 a locking cam 45 pivoted, as at 46, to the drop end adjacent the handle 42 so that when the handle 42 is in substantially vertical position the foot 46' of cam 45 may drop behind said handle 42 and positively hold said handle against clockwise movement. Cam 45 would, of course, have to be moved out of the way, as shown in dotted lines, Fig. 4, before the handle 42 could be moved to operate the device.

As before described, the upper inner corner of the adjustment bracket 23 is chamfered or cut away, as at 28, providing an inclined surface, as shown most clearly in Fig. 5. This surface provides a guiding surface for the outer end of the locking bar 40 to ride upon when the end is being raised to a vertical position.

I claim:

1. In a railway car having a drop end door provided with a bulb angle top chord, the top edge of said door being attached to the web of said angle adjacent the bulb, the flange of said angle depending in a spaced parallel plane with the upper margin of said door, an adjustment bracket attachable to a car side and adjustable in relation to said car side, a latching bar pivoted at one end to said end between said margin and flange and swingable in a plane parallel to said end so as to engage the outer end of said bracket when said end is in closed position.

2. In a railway car having a drop end door provided with a bulb angle top chord, the top edge of said door being attached to the web of said angle adjacent the bulb, the flange of said angle depending in a spaced parallel plane with the upper portion of said door, an adjustment bracket attachable to a car side and adjustable in relation to said car side, a latching bar pivoted at one end to said end between said margin and flange and swingable in a plane parallel to said end and designed to engage the outer end of said bracket when said end is in closed position, a stop lug projecting from said pivoted end and engageable with the web of said angle chord to limit the movement of said latching bar in one direction.

3. In a railway car having a drop end door

provided with a bulb angle top chord, the top edge of said door being attached to the web of said angle adjacent the bulb, the flange of said angle depending in a spaced parallel plane with the upper margin of said door, an adjustment bracket attachable to a car side and adjustable in relation to said car side, a latching bar pivoted at one end to one side of said end between said margin and flange and swingable in a plane

parallel to said end and designed to engage the outer end of said bracket when said end is in closed position, the pivot of said latching bar extending through said end and depending flange, and a handle, on the other side of said end, attached to said pivot for manipulating said latching bar.

4. In a railway car having a drop end door provided with a bulb angle top chord, the top edge of said door being attached to the web of said angle adjacent the bulb, the flange of said angle depending in a spaced parallel plane with the upper margin of said door, an adjustment bracket attachable to a car side and adjustable in relation to said car side, a latching bar pivoted at one end to one side of said end between said margin and said flange and swingable in a plane parallel to said end and designed to engage the outer end of said bracket when said end is in closed position, the pivot of said latching bar extending through said end and said flange, and a handle, on the other side of said end, attached to said pivot for manipulating said latching bar, said handle and latching bar being within the bounding planes of said angle.

5. In a railway car having a drop end door provided with a bulb angle top chord, the top edge of said door being attached to the web of said angle adjacent the bulb, the flange of said angle depending in a spaced parallel plane with the upper margin of said door, a two part adjustment bracket, said parts attachable to a car side and adjustable in relation to each other, an elongated latching bar pivoted at one end to said end between said margin and flange and swingable in a plane parallel to said end and designed to engage the outer end of said bracket when said end is in closed position.

6. In a railway car having a drop end door provided with a bulb angle top chord, the top edge of said door being attached to the web of said angle adjacent the bulb, the flange of said angle depending in a spaced parallel plane with the upper margin of said door, an adjustment bracket attachable to a car side and adjustable in relation to said car side, the inner upper surface of said bracket being upwardly and rearwardly inclined, an elongated latching bar pivoted at one end to said end between said margin and flange and swingable in a plane parallel to said end, said latching bar also designed to engage said inclined surface when the end is being closed and to slide upwardly thereon over said bracket to engage the outer end of said bracket when the end is closed.

7. In a railway car having a drop end door provided with a bulb angle top chord, the top edge of said door being attached to the web of said angle adjacent the bulb, the flange of said angle depending in a spaced parallel plane with the upper margin of said door, a two part adjustment bracket, said parts attachable to a car side and adjustable in relation to each other, an elongated latching bar pivoted at one end to said end between said margin and flange and swingable in a plane parallel to said end and designed

to engage the outer end of said bracket when said end is in closed position and also designed to engage the outer end of said top chord to limit the movement of said bar in one direction, a stop lug projecting from said pivoted end and engageable with said angle to limit the movement of said latching bar in the other direction.

8. In a railway car having a drop end provided with an angle top chord; the combination with a side wall of the car, of a bracket adjustably attached to said side wall, a latching bar pivoted at one end to the interior of said end immediately below said top chord and having its free end projecting beyond the side of said end so as to engage the outer end of the bracket when the end is in upright position, and a stop lug projecting upwardly from the pivoted end of the latching bar and engageable with the web of said top chord to limit the movement of the latching bar in one direction.

9. In a railway car having a drop end provided with an angle top chord; the combination with a side wall of the car, of a corner post secured to the side wall and having a flange overlapping the door when in upright position, a bracket adjustably attached to said side wall adjacent the top of said corner post, a latching bar pivoted at one end to the interior of said end immediately below

said top chord and having its free end projecting beyond the side of said end so as to engage the outer end of the bracket when the end is in upright position, and a stop lug projecting upwardly from the pivoted end of the latching bar and engageable with the web of said top chord to limit the movement of the latching bar in one direction, the free end of said latching bar being engageable with the web of said top chord to limit movement of the latching bar in the other direction.
